UNITED STATES PATENT OFFICE.

MICHAEL CAPIZZI, OF BUFFALO, NEW YORK.

LEG-HOLDER FOR SHOE-POLISHING STANDS.

1,295,693.

Specification of Letters Patent. Patented Feb. 25, 1919.

Application filed September 20, 1918. Serial No. 254,907.

To all whom it may concern:

Be it known that I, MICHAEL CAPIZZI, a subject of the King of Italy, residing at Buffalo, in the county of Erie and State of New York, have invented new and useful Improvements in Leg-Holders for Shoe-Polishing Stands, of which the following is a specification.

This invention relates to a device for holding the foot or leg of a person while the shoe on the same is being shined on a shoe polishing stand. In stands of this character as heretofore generally constructed a foot rest is employed which supports the shoe on its underside and also holds the same against forward movement which necessitates exerting considerable downward pressure by the patron in order to prevent the shoe from being pushed backwardly or sidewise during the polishing operation which is not only inconvenient but also interferes with the shining operation.

It is the object of this invention to provide a leg holder which coöperates with the foot rest and serves to hold the leg both against rearward as well as sidewise motion while the shoe is supported by the rest and is of such construction that it is not difficult to operate and automatically clasps or embraces the leg when placing the foot in the shining position and also automatically releases the leg when the latter is removed from this position, and which can be readily moved into or out of its operative position and also easily adjusted to clasp or grip the leg at different points in its height as may be most desirable.

In the accompanying drawings:

Figure 1 is a fragmentary vertical section of a shoe polishing stand equipped with my improved leg holder. Fig. 2 is a vertical section, on an enlarged scale, taken on line 2—2, Fig. 1. Figs. 3 and 4 are detached elevations of the two sections of the rotary coupling between the leg clasp and the supporting standard. Fig. 5 is a top plan view, partly in section and on an enlarged scale, of the clasp and adjacent parts of the leg holder embodying my invention.

Similar characters of reference refer to like parts throughout the several views.

In its general organization the shoe polishing stand may be like those now in general use, that shown in the drawings comprising a base or body 1 upon the upper part of which is usually a seat for the patron

whose shoes are to be shined while the lower part is provided with a pedestal 2 provided at its upper end with a rest 3 for the underside of the shoe 6 which is to be polished and a rearwardly facing shoulder 4 which is adapted to be engaged by the front side of the heel of the shoe so as to limit the forward motion of the same during the shining operation.

My improved leg holder which is associated with these parts comprises in its general organization a standard which rises from the lower part of the base in rear of the pedestal and foot rest, and a clasp or gripper mounted on the upper part of this standard and adapted to embrace the leg 5 from the rear side thereof.

This standard may be variously constructed but in the preferred form the same is capable of vertical adjustment so as to permit of engaging the clasp with the leg of a person at different points in its height or length. As shown in the drawings this is accomplished by constructing the standard of a lower upright tubular section 7 which is provided at its lower end with an attaching plate 8 whereby the same is secured to the base of the shoe polishing standard and an upper section 9 which slides with its lower end in the lower standard section and is held in its vertically adjusted position thereon by means of a clamp screw 10 arranged on the upper part of the lower standard section and engaging with the lower part of the upper standard section. The upper part of the upper standard section is preferably deflected rearwardly as shown at 11 a sufficient extent to prevent interference therewith of the heel of the shoe which is to be shined when the person is applying the shoe to the foot rest or removing the same therefrom. At its upper end the upper standard section terminates in a forwardly projecting arm 12 upon which is mounted the clasp which is adapted to grasp the leg of the person. This clasp comprises a supporting head 13 which is of substantially horseshoe form and has its sides projecting forwardly and which supports the various movable members of the clasp.

In order to permit this clasp to move out of the way when a person is getting on or off the shoe polishing stand this head is pivotally connected with the arm of the upper standard section so that the same can be swung either downwardly into a pendant inoperative position

sition with reference to this arm, as shown by dotted lines in Fig. 1, or into a horizontal forwardly projecting position with reference to this arm, as shown by full lines 5 in Fig. 1, in which position the same is in operative relation to the foot rest for properly engaging the leg of the person whose shoes are to be shined. This pivotal connection between the head of the clasp may 10 be constructed in any suitable way, but as shown in the drawings the same preferably comprises two coupling sections 24, 25 one of which is connected with the center part of the rear side of the supporting head and the 15 other with the horizontal arm of the standard. The opposing faces of these two coupling sections are preferably made flat and one of these faces, for instance that of the coupling section 24 connected with the sup- 20 porting head, is provided with a plurality of pockets 26 which are arranged in an annular row about the axis of this head, while the flat face of the other coupling section 25 is provided on diametrically opposite sides 25 with two recesses 28, 28 in which are seated two locking or coupling balls 27, 27 which are adapted to engage with pairs of pockets in the other coupling section. The two coupling sections are pivotally connected 30 with each other concentrically with the row of pockets by means of a coupling bolt 29 passing horizontally and transversely through the same, as shown in Figs. 1, 2 and 5. In order to hold the two coupling sec- 35 tions yieldingly in engagement with opposite sides of the two balls between the same, a yielding retaining device is provided which preferably consists of a spring washer 30 arranged around the shank of the pivot bolt 29 and bearing at its outer end against the head of the bolt while its inner end bears against the bottom of a recess 31 in the adjacent part of this coupling section. By this means the clasp can be turned verti- 45 cally either into its operative elevated position or into its inoperative depressed position during which time the pair of locking balls are moved from one pair of locking pockets to another and the spring operates 50 to hold the part yieldingly in whatever position the same may be shifted.

Arranged in front of the supporting head are two laterally movable jaws 14, 14 which are preferably of S-shaped form and each 55 pivoted at its rear end to the front end of one side of the supporting head so as to be capable of swinging horizontally. The front ends of these two jaws are connected by a flexible gripping band which is of sub- 60 stantially U-shaped form and has its loop extending rearwardly into the space between the head and the swinging jaws. This gripping band may be variously constructed but in its preferred form the same comprises an 65 outer section 16 constructed of spring metal

and an inner section 17 constructed of leather, these two sections being preferably co-extensive and having their outer ends turned around the forward extremities of the jaws and secured thereto by means of 70 screws 18 as shown in Fig. 1, or by any other suitable means. The resilience of the outer section of the gripping band operates to throw the gripping jaws apart and to draw the bight of the band forwardly relatively to the jaws and the supporting head. This movement of the jaws and the gripping band is aided by auxiliary means which also operate to guide the rear part of the gripping band relatively to the supporting head. 75 These auxiliary shifting and guiding means, as shown in Fig. 5 preferably comprise a curved follower 19 secured to the rear side of the gripping band by means of a screw 20 or otherwise, two longitudinal guide rods 21, 21 arranged parallel on opposite sides of the longitudinal center of the supporting head and each secured at its front end to the follower adjacent to one end thereof while the rear end of this rod is guided in an opening in the adjacent rear part of the supporting head. This follower together with the guide rods and the rear part of the gripping band is yieldingly moved into its forward position by two springs 22 each of which 80 surrounds one of the guide rods and bears at its front end against the rear side of the follower while its rear end bears against the front side of the supporting head. Forward movement of the follower and the parts connected therewith under the action of the springs 22, 22 is limited by means of stops 23 consisting preferably of pins arranged on the rear ends of the guide rods and engaging with the rear side of the supporting 85 head. 90

Preparatory to engaging this clasp with the leg of a person whose shoes are to be shined, the same is swung upwardly into its operative position at which time its jaws are spread apart and its gripping band drawn forwardly thereby causing the gripping band to assume a position in which a forwardly opening mouth is formed between the front ends thereof, as shown by full lines in Fig. 5. While the clasp is in this position the leg of the person is moved rearwardly through the mouth of the gripping band and into the bight thereof which rearward movement of the leg is continued a sufficient distance to cause the gripping band and the follower to be moved rearwardly in opposition to the springs 22 to produce a rearward pull by the ends of the gripping band on the gripping jaws and automatically swing the latter inwardly into a position shown by dotted lines in Fig. 5. When the parts are in this position the bight of the gripping band engages with the rear and lateral sides of the leg and the front 100 105 110 115 120 125 130

ends of this band and the jaws extend across the front of the leg, thereby embracing the latter with the yielding grip which is however sufficiently firm to reliably hold the 5 same against sidewise motion.

When the polishing of the shoe has been completed it is only necessary for the patron to move his leg forwardly when the clasp 10 will open automatically and release the legs so that the same can be freely disengaged from the clasp. By this means the shoe will be held against displacement on the foot rest without any particular effort on the part of the person being served and the 15 operation of shining the shoe can be accomplished with greater comfort to the patron and also without liability of interfering with the shining operation as the attendant applies the polishing material, and implements 20 to the shoes.

I claim as my invention:

1. A holder for shoe polishing stands comprising a supporting head adapted to receive the leg of a person, two horizontally 25 movable jaws mounted on said head and adapted to extend across the front of said leg, and a flexible band connecting said jaws and adapted to extend around the rear and sides of said leg.
2. A holder for shoe polishing stands comprising a supporting head adapted to receive the leg of a person, two horizontally 30 movable jaws mounted on said head and adapted to extend across the front of said leg, and a flexible band connecting said jaws and adapted to extend around the rear and sides of said leg and comprising an outer 35 section of spring metal and an inner section of leather.
3. A holder for shoe polishing stands comprising a supporting head adapted to receive the leg of a person, two horizontally 40 movable jaws mounted on said head and

adapted to extend across the front of said leg, a flexible band connecting said jaws 45 and adapted to extend around the rear and sides of said leg, and means for yieldingly retaining said band in a forwardly expanded position and said jaws in a separated position. 50

4. A holder for shoe polishing stands comprising a supporting head adapted to receive the leg of a person, two horizontally movable jaws mounted on said head and adapted to extend across the front of said leg, a flexible band connecting said jaws and adapted to extend around the rear and sides of said leg, and means for yieldingly retaining said band in a forwardly expanded position and said jaws in a separated position 60 comprising a follower connected with said band, guiding means connected with said follower and sliding in said head, and spring means interposed between said follower and head. 65

5. A holder for shoe polishing stands comprising a supporting head adapted to receive the leg of a person, two horizontally movable jaws mounted on said head and adapted to extend across the front of said leg, a flexible band connecting said jaws and adapted to extend around the rear and sides of said leg, and means for yieldingly retaining said band in a forwardly expanded position and said jaws in a separated position 70 comprising a curved follower connected with the central part of the rear side of said band, guide rods connected at their front ends with opposite ends of said follower and sliding at their rear ends in said head, 75 springs surrounding said rods and engaging their front and rear ends with said follower and head, and stops arranged on said rods and engaging with the rear side of said head. 80

MICHAEL CAPIZZI.
